OF NEW YORK, N. Y.

DESIGN FOR A CARPET-PATTERN.

Specification forming part of Design No. 6,009, dated July 23, 1872.

Specification describing a new and original Design for a Carpet, invented by DAVID PATON, of Halifax, in the county of York, England.

The accompanying photographic illustration fully represents my new design.

This invention relates to a new carpet-design and border for the same.

The design proper is a scroll-work with projecting leaves and tendrils, and little beads or

fruit on the latter. The two borders are alike. The outer part of each contains rows of semi-circles, while the inner part has inwardly-projecting tufts on an ornamental supporting line.

I claim as my invention—

The design for a carpet, as shown.

DAVID PATON.
